DESIGN FOR A COMBINATION DRAIN AND CUTTING BLOCK

George D. Otis, New York, N. Y.

Application June 30, 1938, Serial No. 78,178

Term of patent 3½ years

To all whom it may concern:

Be it known that I, George D. Otis, a citizen of the United States and residing at 324 West 51st Street, in the city, county, and State of New York, have invented a new, original, and ornamental Design for a Combination Drain and Cutting Block, of which the following is a specification, reference being had to the accompanying drawing, forming a part thereof.

Figure 1 is a view in plan of a combination drain and cutting block showing my new design;

Figure 2 is a view in side elevation of the design;

Figure 3 is a view in section taken in the plane indicated by the line 3—3 of Figure 1 and looking in the direction of the arrows.

I claim:

The ornamental design for a combination drain and cutting block, as shown.

GEORGE D. OTIS.
